UNITED STATES PATENT OFFICE.

WILLIAM L. PAUL, OF SOUTH BEND, INDIANA, ASSIGNOR TO OLIVER CHILLED PLOW WORKS, OF SOUTH BEND, INDIANA.

CULTIVATOR.

1,028,954.

Specification of Letters Patent. Patented June 11, 1912.

Application filed February 26, 1909. Serial No. 480,271.

To all whom it may concern:

Be it known that I, WILLIAM L. PAUL, of South Bend, in the county of St. Joseph and State of Indiana, have invented certain new and useful Improvements in Cultivators; and I do hereby declare the following to be a full, clear, and exact description of the invention, such as will enable others skilled in the art to which it appertains to make and use the same.

This invention relates to improvements in cultivators, and more particularly those of the "gopher" type,—the object of the invention being to so construct the cultivator that the gangs of blades can be raised and lowered or adjusted in such manner that they will move in parallelism both vertically and laterally.

A further object is to so construct a cultivator of the "gopher" type that the working depth of each blade shall be uniform from end to end of the blade.

With these objects in view the invention consists in certain novel features of construction and combinations of parts as herein-after set forth and pointed out in the claims.

In the accompanying drawings, Figure 1 is a plan view of a cultivator embodying my improvements. Fig. 2 is a longitudinal sectional view. Fig. 3 is an enlarged plan view illustrating one of the S-shaped heads and the parts connected therewith. Fig. 4 is a side elevation of the structure shown in Fig. 4, and Fig. 5 is an enlarged detail view showing the connection of the upper end of the yoke.

1 represents the frame of the cultivator mounted at its rear end upon an arch axle 2, the journals of which are supported in carrying wheels 3. A bracket 6 is secured to the rear portion of the frame 1 and to this bracket, a double seat bar 4 is pivotally attached between its ends by means of a pin 5. The forward portions of the seat bar members are curved as at 5^a for a purpose which will hereinafter appear, and on the rear end of the seat bar, a seat 7 is located. The forward ends of the seat bar members embrace a bracket 8 secured to a pole 9, and a coupling pin 10 passes through alined holes in

the seat bar members and a slot 11 in the bracket 8. A vertical pin 13 is pivotally mounted in the pole 9 forwardly of the bracket 8 and is clamped to arch 15. Hounds 16 are pivotally connected at their rear ends with the frame 1 and the forward ends of these hounds are pivoted to collars 17 on the lower horizontal portions 18 of the forward arch. A cross bar 19 is pivoted between its ends to the pole 9 in advance of the forward end of the frame 1, and to the ends of said cross bar, depending clevis bars 20 are pivoted. The lower ends of the clevis bars are connected, by means of links 21 with the forward ends of the hounds 16.

Sleeves 22 are loosely mounted on the laterally projecting arms 18 of the forward arch 15 and each of these sleeves has an arm 23 rigidly clamped thereto. To each arm 23 the forward end of a beam 24 is secured and the rear end of each beam 24 is pivotally attached to a lug 25 which projects from the intermediate portion of an S-shape head 26. Each S-shape head 26 is disposed horizontally and carries a gang of blades. For this reason, sockets or recesses 27 are provided near the respective ends of each head 26 and in these sockets or recesses, shanks 28 are clamped, the lower ends of said shanks having the cultivator blades 29 attached thereto.

Each head 26 is provided with an arm 30 which projects upwardly and slightly forwardly therefrom. The respective members of a yoke 31 are secured at their lower ends to the upwardly projecting arms 30 of the respective S-shaped heads 26 and the upper end of the yoke 31 terminates between the rear arch and the tongue in proximity to the curved portion 5^a of the seat bar, where it is connected with a coupling 32, the latter being, in turn, pivotally attached to the rear portion of a link 33. The link 33 is located above the plane of the frame 1 and is pivotally connected at its forward end with said frame. The beams 24 and link 33 constitute superimposed members pivotally connected at their forward ends with the frame and their rear ends are pivotally connected with the cultivator gangs.

With the construction above described, it will be observed that lines connecting the pivotal points A—B—C—D will form, approximately a parallelogram, and that when 5 a lifting force is applied to the S-shape heads of the cultivator gangs, the latter will be made to rise in parallelism and the long "gopher" blades will be maintained in horizontal positions.

10 An arm 34 is secured to and projects forwardly from an intermediate portion of each S-shape head 26 and to the forward end of each arm 34 the lower end of a chain 35 is attached. The upper ends of the 15 chains 35 are connected with levers 36 and the latter are provided with detents to engage toothed segments 37 secured to the frame 1. By means of these levers and their connections with the arms 34 the cultivator gangs can be raised and lowered or 20 adjusted. It will be observed that the raising and lowering devices are connected with the S-shape heads 26 in advance of the pivotal connections of said heads with 25 the superimposed members consisting of the beams 24 and link 33 and that the said raising and lowering devices also serve to support the cultivator gangs in the positions to which they may be adjusted. Naturally, 30 while at work, there would be a downward thrust at the front points of the blades, but this is met in part by attaching the supporting chains to the arms 34 in advance of the pivotal connection of the beams 24 with 35 the heads 26 and is controlled by the connection of the heads 26 with the link 33 through the medium of the yoke 31.

Foot pieces 38 are secured over the S-shape heads 26 to permit the operator to 40 press the cultivator gangs to their work, and also permit him to shift said gangs laterally in parallelism. This latter operation is effected as follows:—When the operator upon the seat 7, applies pressure to the right 45 hand foot piece, the seat bar will be moved to the left, swinging the inner end of the pole to the right and change the angle of the axle, and frame, and carry the arch 15 with the pole toward the right in parallelism by virtue of the hounds or links 16,—the cultivator gangs being in effect, adjusted laterally and maintained parallel with the line of draft during such adjusting or shifting.

50 Having fully described my invention what I claim as new and desire to secure by Letters Patent, is:—

1. In a cultivator, the combination with 55 framework, a cultivator gang, and a part projecting upwardly from the cultivator gang, of upper and lower members having pivotal connection at their forward ends with the framework, means pivotally connecting the rear end of the lower member 60 with the cultivator gang, means pivotally

connecting the upper member with the upper end of the part projecting upwardly from the cultivator gang, and supporting means connected with said cultivator gang forwardly of the connections between the 70 latter and said members.

2. In a cultivator, the combination with 75 a frame, and beams pivotally supported at their forward ends and capable of free vertical movement on their pivotal supports, a cultivator gang connected by a horizontal pivot to the rear end of each beam, and flexible supporting means attached to said frame and connected at the lower end with the cultivator gangs in advance of the 80 pivotal connection of the latter with the rear ends of said beams.

3. In a cultivator, the combination with 85 a frame, pivoted beams suspended at their forward ends therefrom, and a plurality of cultivator gangs loosely connected with the rear ends of said beams by means of horizontal pivots, of an upwardly projecting yoke connecting the cultivator gangs, a link pivotally attached at one end to the frame 90 and having pivotal connection at its other end with said yoke, and supporting means for the cultivator gangs connected with said gangs in advance of the pivotal connections between said gangs and the beams. 95

4. In a cultivator, the combination with 100 a frame and pivoted beams suspended therefrom, of heads pivoted between their ends by horizontal pivots to the rear ends of said beams and at an angle to the latter, shanks secured to each head, cultivator blades carried by the shanks, arms projecting forwardly from the pivotal connection between the beams and heads, and means connected with said forwardly projecting 105 arms for adjusting the gangs vertically and for supporting them.

5. In a cultivator, the combination with 110 a frame and pivoted beams suspended therefrom, of S-shaped heads, each pivotally attached between its ends to the rear end of one of said beams, vertical shanks clamped to the respective ends of each S-shaped head, cultivator blades carried by said shanks, a link pivoted at one end to the frame, a yoke pivotally attached to the other end of said link and connected with the respective heads between the ends of the latter, and means connected with said heads for raising, lowering and supporting the 120 same and the cultivator blades carried thereby.

6. In a cultivator, the combination with 125 a frame, an arch, and means on the frame for supporting said arch, of rearwardly projecting arms loosely connected with the ends of said arch, beams secured to said arms and projecting rearwardly therefrom, heads pivotally connected between their ends by horizontal pivots with the rear ends of said 130

beams, shanks secured to said heads, cultivator blades carried by said shanks, arms on said heads projecting forwardly from the pivotal connection of the heads with the
5 beams, pivoted operating levers, and chains connecting said levers with the forwardly projecting arms of the heads.

In testimony whereof, I have signed this specification in the presence of two subscribing witnesses.

WILLIAM L. PAUL.
